UNITED STATES PATENT OFFICE.

ALBERT E. READE, OF PETERSBURG, VIRGINIA.

WINDOW AND SASH.

Application filed July 29, 1924. Serial No. 728,962.

To all whom it may concern:

Be it known that I, ALBERT E. READE, a citizen of the United States, residing at Petersburg, in the county of Dinwiddie and 5 State of Virginia, have invented certain new and useful improvements in Windows and Sashes, of which the following is a full, clear, and exact description.

This invention relates to windows and window sashes and more particular to such devices designed for use in closed automobiles such as sedans. It is a well known fact that many injuries both serious and slight are caused by broken and flying glass 10 when automobile windows are shattered by collisions and other accidents. It is therefore an object of the present invention to provide a substitute for the ordinary glass windows which while entirely transparent 15 is not brittle and therefore contains no potential power of injury to passengers by cutting and the like.

A further object of the invention resides in the construction of a metallic sash or frame for a transparent window panel which is united to the panel by the same means which unites the respective ends of the frame sections, and in which the joints between the frame sections are so designed 20 as to cause the same to lie in a single plane.

Other objects and advantages of the invention will be apparent from the following description when taken in connection with the accompanying drawings, in which,

Figure 1 is a fragmentary perspective view of a door of an automobile with my improved window and frame in place.

Figure 2 is a plan view of the window and frame per se.

Figure 3 is a fragmentary plan view of one of the joints of the frame.

Figure 4 is a fragmentary section through the plane of the window.

Figures 5 and 6 are sections taken on lines 45 5—5 and 6—6 respectively Figure 3.

Figure 7 is a broken-away perspective view of one of the frame members, and

Figure 8 is a fragmentary perspective view of a corner of the window.

Referring to the drawings more in detail the numeral 1 indicates the door of an automobile of the closed type for which the present invention is intended. Such doors are provided with vertical grooves or guide-

ways 2 in which the window is adapted to 55 slide and such an arrangement is shown in Figure 1 with the window indicated generally by the letter "A" in place.

The transparent panel of which the window is formed may be composed of celluloid or other transparent composition of flexible material and is designated throughout the drawings by the numeral 3. The transparent panel of window must of course be held against flexing and to this end I 60 have provided a metallic frame or sash which is composed of four metallic sections which are of identical design. Each section of the frame is stamped-up from sheet metal into a channel formation as indicated 65 by the numeral 4 and is adapted to receive 70 by the numeral 4 and is adapted to receive one edge of the transparent panel 3.

Obviously, in order that the sash may fit snugly within the guideways 2 it is necessary that the sash should be of the same 75 thickness throughout. Therefore, opposite ends of each of the side walls of the sash sections are cut away as indicated by the numeral 5 thus permitting a joint to be formed as more clearly shown in Figure 8. 80 In order that the joint may entirely enclose the edge of the transparent panel it will be seen that the base of the channel is not cut away and thus forms a closure 7 for the end of the adjacent section of the frame. 85 The ends of the respective sections 4 are united by means of one or more countersunk rivets 6 which also pass through the corner of the transparent panel and securely 90 holds the several elements in place.

From the foregoing description it will be apparent that I have devised a simple and inexpensive window and sash which will eliminate the danger inherent in broken and flying glass in automobile collisions 95 and yet which has practically all of the advantages of glass windows.

In accordance with the patent statutes I have described what I now believe to be the best embodiment of the invention, but I do not wish to be understood thereby as limiting myself or the scope of the invention, as many changes and modifications may be made without departing from the spirit of the invention; all such I aim to include in 100 the scope of the appended claim.

What I claim as new and desire to secure by Letters Patent is:

In a device of the class described a transparent imperforate panel of flexible material, a metallic frame formed of four sections in which said panel is positioned, each section comprising a base portion extending throughout the length of the section and side walls of shorter length than the section,

one side wall terminating short of one end of the section and the other side wall terminating short of the other end of the section, and rivets uniting the ends of adjacent sections.

ALBERT E. READE.
